PLATFORM FOR A SAW HORSE

Harry R. Bellaire, Buchanan, Mich., assignor to Southwestern Tool Corporation, Buchanan, Mich., a corporation of Michigan

Filed Sept. 17, 1965, Ser. No. 87,051

Term of patent 14 years

(Cl. D54—1)

FIG. 1

FIG. 2

FIG. 3

FIG. 4

FIG. 5

FIG. 6

FIG. 7

FIGURE 1 is a perspective view of a platform for a saw horse, showing my new design, with the legs shown in broken lines for illustrative purposes only;

FIGURE 2 is a top plan view thereof;

FIGURE 3 is a side elevational view of the side opposite to that shown in FIGURE 1;

FIGURE 4 is a bottom view;

FIGURE 5 is a horizontal cross sectional view, taken on line 5-5 of FIGURE 2;

FIGURE 6 is an elevational view of the end opposite that shown in FIGURE 1; and

FIGURE 7 is a cross sectional view taken on line 7-7 of FIGURE 2.

I claim:

The ornamental design for a platform for a saw horse, substantially as shown and described.
